US00D977457S

(12) **United States Design Patent** (10) Patent No.: **US D977,457 S**
Bullimore et al. (45) Date of Patent: **** Feb. 7, 2023**

(54) **WAVEGUIDE**

- (71) Applicant: **Tymphony Acoustic Technology Limited**, Taipei (TW)
- (72) Inventors: **George Albert Bullimore**, Huizhou (CN); **Stuart Martin Hancock**, Huizhou (CN); **Gavin Jones**, Huizhou (CN)
- (73) Assignee: **TYMPHANY ACOUSTIC TECHNOLOGY LIMITED**, Taipei (TW)
- (**) Term: **15 Years**
- (21) Appl. No.: **29/825,534**
- (22) Filed: **Feb. 2, 2022**

Related U.S. Application Data

- (62) Division of application No. 29/725,083, filed on Feb. 21, 2020.

(30) **Foreign Application Priority Data**

Primary Examiner — Paula Allen Greene*(74) Attorney, Agent, or Firm* — Muncy, Geissler, Olds & Lowe, P.C.**CLAIM**

The ornamental design for a waveguide, as shown and described.

DESCRIPTION

FIG. 1 is a perspective view of a waveguide showing our new design;

FIG. 2 is a top plan view thereof;

FIG. 3 is a bottom plan view thereof; and,

FIG. 4 is a side plan view thereof.
